(57) **CLAIM**

The ornamental design for a jar, as shown and described.

DESCRIPTION

FIG. 1 is a front elevation view of a jar showing my new design;

FIG. 2 is a side elevation view thereof;

FIG. 3 is another side elevation view thereof;

FIG. 4 is a top plan view thereof;

FIG. 5 is a bottom plan view thereof; and,

FIG. 6 is a side perspective view thereof.

The broken lines in the drawings showing of the jar illustrate the portions of the jar that form no part of the claimed design.
